COMBINED WASTE RECEPTACLE AND TRAY

Mario Manfredonia, Nassau County, N.Y.
(2 Emerald Drive, Glen Cove, N.Y.)

Filed Aug. 7, 1964, Ser. No. 81,194

Term of patent 14 years

(Cl. D58—17)

FIG. 1

FIG. 2

FIG. 1 is a front perspective view of a combined waste receptacle and tray embodying my new design; and,
FIG. 2 is a front elevational view thereof.

The rear and side not shown are substantially plain and unornamented.

I claim:

The ornamental design for a combined waste receptacle and tray, as shown and described.
